PILLOWCASE OR SIMILAR ARTICLE OF BED LINEN

Leonard C. Clementi, Huntington, N.Y., assignor to Cannon Mills Company, Kannapolis, N.C., a corporation of North Carolina

Filed Oct. 30, 1967, Ser. No. 9,219

Term of patent 14 years

(Cl. D92—26)

The essential features of my design reside in the full line disclosure on the border.

I claim:

The ornamental design for a pillowcase or similar article of bed linen, substantially as shown and described.
